UNITED STATES PATENT OFFICE.

WILLIAM C. HENDERSON, OF BALTIMORE, MARYLAND.

DESIGN FOR A SIGN.

No. 40,045.

Specification for Design.

Patented June 8, 1909.

Application filed April 5, 1909. Serial No. 488,135. Term of patent 7 years.

To all whom it may concern:

Be it known that I, WILLIAM CHARLES HENDERSON, a citizen of the United States, residing at Baltimore, in the State of Maryland, have invented a new, original, and ornamental Design for Signs, of which the following is a specification, reference being had in the accompanying drawing, forming part thereof.

The figure is a side elevation of a sign, showing my new design.

The essential features of my design are the diagonal divisional lines with a horseshoe at their intersection.

I claim:

The ornamental design for a sign, as shown and described.

WILLIAM C. HENDERSON.
